Filed Oct. 29, 1963, Ser. No. 77,187

Term of patent 14 years

(Cl. D31—3)

FIG. 5

FIG. 1

FIG. 2

FIG. 3

FIG. 4

FIG. 1 is an enlarged side elevational view of a sprayer pump handle or similar article showing our new design, the opposite side being substantially a mirror image of the side shown;

FIG. 2 is a rear elevational view thereof;

FIG. 3 is a front elevational view thereof;

FIG. 4 is a bottom plan view thereof; and

FIG. 5 is a cross-section taken on line 5—5 of FIG. 1. The dominant features of our design reside in the full line portions and the nozzle and hose coupling assembly are disclosed in broken lines for illustrative purposes only.

We claim:

The ornamental design for a sprayer pump handle or similar article, substantially as shown and described.
